MOUTHPIECE FOR MORTICIANS

Richard J. Embser, Wellsville, N. Y.

Application August 4, 1944, Serial No. 548,092

5 Claims.

(Cl. 27—1)

This invention relates to a mouthpiece for morticians.

A primary object of this invention is the provision of a mouthpiece adapted to be utilized by morticians to support the mouth and lip contour of deceased persons having no teeth.

An additional object is the provision of such a mouthpiece which will give a natural and life-like expression to the mouth and lip contour of a corpse.

A still further object is the provision of an improved device to assist a mortician in his work about the mouth and lips of a corpse.

A still further object is the provision of such a device which may be readily adjusted to provide the corpse with such facial expression as may be desired.

Other objects will in part be obvious and in part be pointed out as the description of the invention proceeds and in part shown in the accompanying drawing, wherein there is depicted a preferred embodiment of this inventive concept.

In the drawing:

Figure 1 is a top plan view of a device embodying one form of this invention.

Figure 2 is a front elevational view of the device of Figure 1.

Figure 3 is a rear elevational view of the device, and

Figure 4 is a sectional view taken substantially along the line 4—4 of Figure 1.

Like reference numerals refer to like parts throughout the several views of the drawing.

The device is comprised of a semi-circular flat plate 10 provided with protrusions 11 adapted to be positioned between the lips and the gums of a deceased person, projections 11 serving to hold the same firmly in position. Secured to the concave surface of plate 10 in any suitable manner as by rivets 12 is a double flange 13 of substantially U-shaped cross-sectional configuration, and conforming generally to the circular configuration of plate 10 but being slightly smaller in diameter. Portion 13 is formed with a series of serrations 14 tapered toward the back thereof to provide a plurality of teeth 15, the extremities of which may be moved toward and away from each other to accommodate the size of the member to varying sizes of mouths. Similarly, opposite teeth, which are adapted to be positioned between the gums of the corpse may be bent toward each other to allow for a variety of expressions.

Projections 16 are also provided on the upper and lower surfaces of the teeth 15 in order to hold the same securely between the gums without possibility of slippage.

It will now be seen that the member 10 may

be readily bent to a variety of arcs and curvatures and likewise the member 15 may be correspondingly bent. It will also be seen that the space between the teeth 15 may be varied as above indicated to provide for varying spacings between the gums of the corpse.

From the foregoing it will now be seen that there is herein provided a device accomplishing all the objects of this invention and others including advantages of great practical utility.

As many embodiments may be made of this inventive concept, and as many modifications may be made in the embodiment herein shown and described, it is to be understood that all matter herein is to be interpreted merely as illustrative and not in a limiting sense.

I claim:

1. In a mouthpiece for the use of morticians, a semi-circular plate adapted to fit between the lips and the gums of a corpse, and a flange-like semi-circular member secured to and extending from the concave portion of said plate and adapted to be positioned between the gums.
2. In a mouthpiece for the use of morticians, a semi-circular plate adapted to fit between the lips and the gums of a corpse, and a flange-like semi-circular member secured to and extending from the concave portion of said plate and adapted to be positioned between the gums, said member being of a normal thickness approximating the width of the teeth.
3. In a mouthpiece for the use of morticians, a semi-circular plate adapted to fit between the lips and the gums of a corpse, a flange-like semi-circular member secured to and extending from the concave portion of said plate and adapted to be positioned between the gums, said member being of a normal thickness approximating the width of the teeth, and means whereby the thickness of said plate may be varied.
4. In a mouthpiece for the use of morticians, a semi-circular plate adapted to fit between the lips and the gums of a corpse, a flange-like semi-circular member extending from and secured to the concave portion of said plate, adapted to be positioned between the gums, and means for varying the radius of curvature of said member.
5. In a mouthpiece for the use of morticians, a semi-circular plate adapted to fit between the lips and the gums of a corpse, a flange-like semi-circular member extending from and secured to the concave portion of said plate, adapted to be positioned between the gums, and means for varying the radius of curvature of said member, said last-mentioned means comprising a plurality of serrations cut through the walls of said flange-like member.

RICHARD J. EMBSER.
